UNITED STATES PATENT OFFICE.

ROBERT BREYER, OF MILWAUKEE, WISCONSIN, ASSIGNOR TO PHOENIX KNITTING WORKS, OF MILWAUKEE, WISCONSIN, A CORPORATION OF WISCONSIN.

SAFETY DEVICE.

Application filed December 29, 1921. Serial No. 525,799.

To all whom it may concern:

Be it known that I, ROBERT BREYER, a citizen of the United States, residing at Milwaukee, in the county of Milwaukee and 5 State of Wisconsin, have invented a certain new and useful Improvement in Safety Devices, of which the following is a full, clear, concise, and exact description, reference being had to the accompanying drawings, forming a part of this specification.

My invention relates to protective devices for guarding the moving parts of machinery to protect the operator and others from accidental injury thereby. More specifically 15 it relates to means for guarding the hand wheel of full fashion machines.

In the machine in common use for this work, the operator must be able to stop the machine when standing at any point along 20 the length thereof, and must also be able to turn the machine slowly by hand while adjusting the needles and other parts of the knitting mechanism. For this purpose a small control shaft is provided, located in 25 front of the machine and substantially level with the work, which shaft may be slid longitudinally to complete an electric circuit for driving the machine by power. Below the control shaft there is a larger 30 shaft geared to the driving mechanism of the machine, and equipped with a plurality of hand wheels at spaced intervals, so that wherever the operator happens to be, he can always readily grasp one of the hand 35 wheels with one hand and turn the machine to observe the operation of the knitting unit in front of which he is standing. The foregoing structure is old and well known in the art and per se forms no part of my 40 present invention.

While I am at present unable to state definitely whether the charge originates in the friction of the knitting needles with the silk thread or not; it is a fact that in operation 45 these machines pick up a rather heavy charge of static electricity, especially in damp weather just before a rain. The resultant tendency of the machine, and especially of the rotating hand wheels, to attract the clothing of anyone coming near them, involves less risk to the operators than would ordinarily be anticipated, partly because the operators are usually men, and partly because the operator is continually 50 touching various metallic parts of the ma-

chine, so that his body and clothes pick up more or less of the charge of the machine, sometimes to such an extent the garments of the operator are repelled from, rather than attracted towards the hand wheels. 60 The risk to others who have to walk near the machine in the course of their duties, is, however, somewhat increased by the apparent immunity of the operator, which tends to render them less cautious, whereas 65 they should be more so.

The primary object of my invention is to eliminate the dangers above outlined.

Another object is to provide the necessary protection without interfering with 70 the efficiency of the operator.

The most obvious difficulties in the way of accomplishing the last mentioned object are that the hand wheels must be freely accessible to the operator whenever the machine is stopped, otherwise the operator would have difficulty in making adjustments; and that the protection must be available whenever the machine is running without any additional movement on the 75 part of the operator, otherwise a careless operator would forget to use the device.

The accompanying drawings illustrate as much as is necessary of a full fashioned knitting machine to show the application of 85 my invention thereto.

Figure 1 is a perspective view of a portion of the control shaft and hand operating shaft of such a knitting machine, and

Fig. 2 is a detail section of the end of 90 the control shaft.

In the embodiment of my invention selected for illustration the control shaft 10 extends horizontally from end to end of the machine, and the hand-drive shaft 12 is 95 parallel with and spaced below the same. One of the hand wheels is illustrated at 14. The end of shaft 10 carries a block of insulation 16 on which is mounted a metallic contact 18 adapted to bridge the gap between 100 two contacts 20 and complete the electric circuit for driving the machine by power. The structure just described embodies the essential features of the device of the prior art to which my invention has been applied. 105

According to my invention I mount a plurality of curved guards 22 on the control shaft 10, preferably keying them as at 24 to prevent rotation around the axis of shaft 10. The shaft itself is, of course, pre- 110

vented from rotation by similar means (not shown). It will be apparent, that longitudinal movement of control shaft 10 to carry contact 18 toward or away from contacts 20 will move the guard 22 into or out of a position directly over hand wheel 14, where it will protect those near the machine from accidental injury.

The distance through which contact 18 need be moved, however, in order to make and break the operating circuit for the machine, is so small that the range of movement of guard 22 would be insufficient to carry it from a position directly over hand wheel 14, to a position far enough at one side not to interfere with the hand of the operator. I have provided a lost motion connection for increasing the range of movement of control rod 10 and guard 22. Reference to Fig. 2 an extension 26 is slidably mounted in the tubular end of rod 10 and urged resiliently to the left by spring 28. A pin 30 limits the relative movement of the sleeve and extension. A fixed bearing 32 guides the extension 26, and a collar 34 fastened on the extension by suitable means, such as set screw 36, limits the movement of the extension to the left, and prevents the force applied by the operator to control rod 10 from being imposed on contacts 18 and 20. Spring 28 should preferably be strong enough to overcome the friction of extension 26 in rod 10 and bearing 32, but of insufficient strength to force contact 18 into place between contacts 20, and entirely ineffective to overcome the frictional resistances or rod 10 in its bearings. The operator must, therefore, move rod 10 until pin 30 encounters the right hand end of its slot before he can force contact permanently into place, and to stop the machine he must move the rod until pin 30 contacts the left hand end of its slot. This prevents him from stopping the machine by partial movement of control rod 10, and cramping or hurting his hand by trying to rotate wheel 14 while it is too close to guard 22. At the same time he can move the machine by power a little at a time, by a temporary light contact between parts 18 and 20, without taking up the lost motion provided by the pin 30 in its slot, while his hand is continually in contact with wheel 14 and he moves the machine a little by power, or by hand, or both. When he finds the operation of the knitting mechanism satisfactory, he can release hand wheel 14 and throw control rod 10 completely over, leaving the machine running

at full speed with guards 22 in operative position.

Without further elaboration, the foregoing will so fully explain the gist of my invention, that others may, by applying current knowledge, readily adapt the same for use under various conditions of service, without eliminating certain features which may properly be said to constitute the essential items of novelty involved, which items are intended to be defined and secured to me by the following claims.

I claim:

1. In a control system for knitting machines, manual operating means, manual power control means, and protector means associated with said manual power control means and arranged to be moved into position to shield and protect the manual means, when the power means is in operation.
2. In a control system for knitting machines having a longitudinally slidable power control rod and a hand drive wheel, the combination with said rod of a guard carried thereby and arranged to cover said wheel when the power is turned on.
3. In a control system for knitting machines having a longitudinally slidable power control rod and a hand drive wheel, the combination with said rod of a guard carried thereby and arranged to cover said wheel when the power is turned on, control means actuated by said rod, and a lost motion connection between said rod and said control means.
4. In a control system for knitting machines having a longitudinally slidable power control rod and a hand drive wheel, the combination with said rod of a guard carried thereby and arranged to cover said wheel when the power is turned on, control means actuated by said rod, and a lost motion connection between said rod and said control means, said control means permitting temporary operation of said machine by power without taking up the lost motion.
5. In combination with a machine having a power control element and a manual drive element, power delivery means operable by either partial or complete actuation of said control element, and guard means for covering said manual drive element when said control element is completely actuated, but not when it is partially actuated or in inoperative position.

In witness whereof, I hereunto subscribe my name this 21st day of December, 1921.

ROBERT BREYER.
